UNITED STATES PATENT OFFICE.

IVAR A. RANDEL AND ALVIN C. McCORD, OF CHICAGO, ILLINOIS.

T-PIN FOR AXLE-BOX LIDS.

1,146,953.

Specification of Letters Patent. Patented July 20, 1915.

Application filed December 14, 1914. Serial No. 877,063.

To all whom it may concern:

Be it known that we, IVAR A. RANDEL and ALVIN C. McCORD, citizens of the United States, residing at Chicago, in the county of Cook and State of Illinois, have invented certain new and useful Improvements in T-Pins for Axle-Box Lids; and we do hereby declare the following to be a full, clear, and exact description of the invention, such as will enable others skilled in the art to which it appertains to make and use the same.

Our invention relates to car axle boxes, and more particularly to lid structures of the type disclosed and claimed in Letters Patent of the United States, No. 803,155, granted to W. G. Dunham, of date, October 31st, 1905, and entitled "Car axle box lids", and in a modified form of the Dunham box disclosed and claimed in Letters Patent No. 1,095,737, to William C. Reed, of date, May 5th, 1914. In the construction shown in the said two patents above identified, T-pins or bolts are employed in coöperation with springs to yieldingly hold the lids in closed and also in opened positions. In practice, it was found that these T-pins were decidedly too frail when cast in ordinary gray iron, and it was further found that even when the pins were made of malleable iron, they would frequently break. Also, malleable T-pins are very liable to have flaws, so that it became necessary to test all of the pins before applying them.

Our present invention provides a cheap, strong and durable substitute for the cast T-pins, and involves stamping a blank from sheet metal, and in folding this blank together to form the completed T-pin.

In the accompanying drawings which illustrate the invention, like characters indicate like parts throughout the several views.

Referring to the drawings: Figure 1 is a vertical section showing a journal box and lid of the general type above indicated, and showing the improved T-pin applied to a journal box and lid of the particular construction disclosed in the said Reed patent above identified, some parts of the said box being broken away. Fig. 2 is a fragmentary view in elevation showing the upper portion of the box and a portion of the T-pin applied thereto; Fig. 3 is an enlarged section taken on the line $a^a - w^w$ on Fig. 2; Fig. 4

shows the pin in blank form, or as cut from the sheet of steel; Fig. 5 shows the pin partly bent; Fig. 6 shows the completed pin; and Fig. 7, is a perspective view showing a slightly modified form of the T-pin.

The numeral 1 indicates an axle box which, at its upper portion, adjacent to its mouth opening, is formed with a heavy hinge lug 2 having trunnion seats 3. The trunnion seats 3, as shown, are provided with trunnion entrance channels 4, and just to the rear thereof, is formed with an upwardly extended lock shoulder 5. The lug 3, in its outer surface, is provided with laterally spaced flanges 6 formed on their adjacent faces with trunnion seats 7 having contracted forwardly extended channels 8.

The lid 9 is provided at its upper portion with a central pocket 10 that bulges outward and embraces the hinge lug 3 of the box. On its sides, the pocket 10 is formed with axially alined inwardly projecting trunnions 11, shown as flattened and thereby given such dimension that they can be passed through the entrance channels 4, only when the flattened trunnions are turned into alignment with said channels. When the lid is closed, the upper edge of the hood 10 engages the shoulder 5 of the lug 2, and a lock flange 13 on the lower portion of the lid engages a rib 14 formed on the lower edge portion of the box opening. The lid is thus normally held locked in a closed position, but the elongated trunnion seats 3 permit sufficient vertical movement of the box to disengage the flanges 13 from the rib 14 and the upper edge of the hood 10 from the shoulder 5, which disengagement is, of course, necessary in order to permit the lid to be released for pivotal movement into an open position. The lid 9, on its inner face, has a rigidly secured inwardly projecting perforated lug or bracket 13^a, through which the stem of the T-bolt, presently to be described, is passed.

The construction so far described is substantially identical with that disclosed in the said Reed patent above noted, and so far as this present invention is concerned, is capable of many modifications.

Fig. 4 shows the form in which a T-bolt is stamped from a sheet of steel. The head and stem forming portions thereof, are indi-

cated, respectively, by the numerals 15 and 16. The stem is formed on its opposite sides with off-set shoulders 17 and 18. The dotted line marked 19 in Fig. 4 indicates the line on which the head 15 is bent when the blank is bent to form the pin, as illustrated in Fig. 6. Here it is important to note that said pin-forming blank, Fig. 4, is bi-symmetrical on opposite sides of the dotted line 19, so that when the pin is completed, the two stem-forming portions, the two sides of the head-forming portion, the lugs 17-17 and the lugs 18-18, will be brought into true registration, thereby forming a single pin, the thickness of which is represented by the two thicknesses or layers of the steel sheet from which the pin was stamped. It is also important to note that the upper edge of the head 15 is rounded so as to give the desired bearing against the seats 7 (see Fig. 3); and it is also important to note that the sides of the ends of the said head are flattened and of such dimensions that they will pass through the entrance channels 8 to the said seats 7, when the pin is turned into alignment with the said channels 8. Also, it will be noted by reference, particularly, to Fig. 3, that the ends of the head 15, measured in the longitudinal plane of the pin, are such that they will not pass through the entrance channels 8 when the pin is turned out of alignment with said channels. Further, it may be noted that the shoulders 17-17, longitudinally of the pin, are off-set slightly from the shoulders 18-18, so as to compensate for the angularity in the end of the co-operating coiled spring 20. The said coiled spring 20 is placed around the stem of the T-pin and is compressed between the shoulders 17-18 of the said pin, and the pin surrounding portion of the lid bracket 16.

In actual practice, the efficiency of the T-pin above described, for the purposes had in view, has been fully demonstrated.

The T-pin shown in Fig. 7 is like that shown in Figs. 1 to 6 inclusive except that the head 15^a is not folded closely upon itself, and the stem forming portions 16^a are bent to approximately semi-cylindrical cross sec-

tion so as to form an approximately cylindrical stem. 50

What we claim is:

1. A T-pin of the kind described, formed from a single piece of sheet metal, having a stem-forming portion, and having relatively wide bi-symmetrical head-forming portions folded to form the complete pin. 55

2. A T-pin of the kind described, formed from a single piece of sheet metal and having bi-symmetrical head and stem forming portions folded together, the stem of the said pin having projecting lugs against which a coiled spring is adapted to be seated. 60

3. A T-pin of the kind described, formed from a single piece of sheet metal and having bi-symmetrical head and stem forming portions folded together, the stem of the said pin having oppositely projecting lugs against which a coiled spring is adapted to be seated, the lugs on one side of said stem 70 being longitudinally offset from the lugs on the opposite side thereof. 65

4. A T-pin of the kind described, formed from a single piece of sheet metal and having bi-symmetrical head and stem forming portions folded together, the ends of the folded head of said pin being flattened in the plane of the pin. 75

5. A pin of the kind described, formed from a single piece of sheet metal, having a stem forming portion and bi-symmetrical head forming portions folded to form the completed pin. 80

6. A T-pin of the kind described, formed from a single piece of sheet metal, having a stem forming portion and bi-symmetrical head forming portions folded to form the completed pin, the ends of the folded head having flattened sides for the purposes set forth. 85

In testimony whereof we affix our signatures in presence of two witnesses.

IVAR A. RANDEL.
ALVIN C. McCORD
